UNITED STATES PATENT OFFICE.

JEROME W. WELCH, OF SERGEANT BLUFF, IOWA.

CONCRETE STRUCTURE HAVING WATERPROOFING REINFORCEMENT.

1,393,592.

Specification of Letters Patent. Patented Oct. 11, 1921.

Application filed February 18, 1919. Serial No. 277,791.

To all whom it may concern:

Be it known that I, JEROME W. WELCH, a citizen of the United States, residing at Sergeant Bluff, in the county of Woodbury 5 and State of Iowa, have invented certain new and useful Improvements in Concrete Structures Having Waterproofing Reinforcements, of which the following is a specification.

10 My invention relates to new and useful improvements in reinforced concrete structures, the primary object of my invention being the provision of a waterproofing reinforcement which may be employed in constructing concrete blocks for building purposes or which may be employed in the building of monolithic concrete walls.

15 A still further object of my invention is the provision of a metallic reinforcement in the nature of a partition wall which may be spaced any desired extent from the weather face of the block or wall in which it is incorporated and which carries a plurality of reinforcing anchoring elements which are 25 embedded in the concrete.

20 In concrete blocks, the partition wall or main body of the reinforcing element extends throughout the length and breadth of the block and at its edges is adapted for locking engagement with the reinforcing elements of adjacent blocks so that in a 30 finished structure a thin metallic wall is in effect provided between an inner and outer wall, although the parts are so firmly united 35 and braced that there can be no separation between them.

Another object which I have in view is the provision of novel means for locking the 40 ends of adjacent blocks together, and a novel means for holding the blocks of one course in a wall construction from movement with respect to the blocks of another course.

Another object which I have in view is the provision of means for insuring proper 45 positioning of the reinforcing elements during construction of the wall and to provide additional bracing devices for the wall.

With these and other objects in view, my invention will be more fully described, illustrated in the accompanying drawings, and 50 then specifically pointed out in the claims which are attached to and form a part of this specification.

In the drawings:

55 Figure 1 is a side elevation of my com-

plete reinforcing device as employed in the manufacture of solid concrete blocks;

Fig. 2 is a longitudinal sectional view taken on the line 2—2 of Fig. 1;

Fig. 3 is a vertical sectional view taken on 60 the line 3—3 of Fig. 1, looking in the direction of the arrows;

Fig. 4 is a section taken on the line 4—4 of Fig. 1 and also looking in the direction 65 of the arrows;

Fig. 5 is a fragmentary elevation of a wall constructed with my reinforced concrete blocks;

Fig. 6 is a fragmentary horizontal sectional view taken through the joint between 70 the ends of adjacent blocks of the same course;

Fig. 7 is a fragmentary vertical sectional view taken on the line 7—7 of Fig. 5, showing the manner of holding blocks of adjacent courses against independent movement 75 or displacement;

Fig. 8 is a side elevation of the metallic reinforcing element employed in building a 80 monolithic concrete wall;

Fig. 9 is a longitudinal sectional view taken on the line 9—9 of Fig. 8;

Fig. 10 is a vertical sectional view taken on the line 10—10 of Fig. 8.

85 My improved metallic reinforcement includes a rectangular body 10 of sheet metal of any desired length, breadth and thickness, the length and breadth of the sheet being substantially that of the block in which it is to be used. Secured along the ends of 90 the body member and against both sides thereof are strips of sheet metal 11 which project beyond the ends of the body and are bent outwardly away from each other and then rebent toward each other to provide hooks 12. As best shown in Fig. 2, 95 the hooks are opposed to each other with their bills spaced somewhat apart. Secured against opposite faces of the body 10 along each side edge are strips 13 which, at their ends, abut against the inner edges of the strips 11 and which project somewhat beyond the edges of the body to provide channels 14, as shown in Figs. 3 and 4. The 100 end strips 11 are formed intermediate their widths with relatively wide slots 15 running parallel with the ends of the body. Secured over the end strips 11 are outer end strips 16 which terminate at their ends flush 105 with the outer edges of the side strips 13 110

and which are formed with relatively narrow slots 17 enlarged at one end to provide an opening 18 equal in width to the slots 15. These narrow slots 17, together with their continuations 18, are equal in length to the slots 15 and serve as anchoring seats for a number of reinforcing elements 19. Each of these reinforcing elements includes a body 20 of sheet metal having its outer end bifurcated and the arms thus formed bent laterally in opposite directions to provide anchoring members 20, as clearly shown in Figs. 1 and 2 and having its inner end bent at a right angle, as shown in Fig. 2. Secured to the body portion of these strips 19, adjacent the ends 21, are strips 22 which have their free ends bent at right angles, as shown at 23 to lie in the plane of the terminals 21 of the strips. The portions 21 and 23 thereby form seating heads which may be passed through the openings 18 and into the slots 15, the portions connecting these heads with the remainder of the reinforcing element being slidable in the slots 17. By this means, a number of the reinforcing elements 19 may be applied to the ends of the main reinforcing element or structure 10 at either side.

Extending longitudinally of the body 10 and along both sides and in parallel spaced relation to the side strips 13 are supporting strips of sheet metal 24 which, at intervals, are out struck to provide pockets 25 capable of receiving the terminals 26 of substantially Z-shaped reinforcing elements 27. Each of these elements is in the form of a strip of sheet metal having its end portions bent at right angles to its intermediate portion. These reinforcing elements 27 are employed only along the upper part of the body 10 and, of course, have their ends hooked downwardly into the pockets and their other ends directed upwardly. Somewhat similar reinforcing elements 28 are provided for the lower portion of the body in which the outer ends are bent parallel with the inner ends so that the outer ends may extend downwardly when the inner ends engage in the pockets. Obviously, any number of pockets may be provided and a number of reinforcing elements 27 and 28 employed and the space at which they are positioned may be altered at will.

Extending longitudinally of the body at each side and substantially midway of its height, are strips 29 of corrugated sheet metal, the corrugations of which, together with the body 10, provide a series of pockets 30. U-shaped reinforcing loops 31, of wire or equivalent material, have their end portions bent into parallel spaced relation in a plane at right angles to the body portion to engage in these pockets 30 so that the intermediate or U-shaped portions of the devices 31 will project at right angles to the main

body 10. Any desired number of these bracing members 31 may be employed at each side of the body 10 but preferably they are so arranged as to slightly overlap each other, as shown in Figs. 1 and 2 of the drawings.

The above described structure constitutes the reinforcing element or member proper of a concrete block and in making the block such reinforcing member is embedded between the front and back walls of the block with which it is coextensive. The reinforcing structure is preferably embedded in the block so that its body is located from one-third to one-half the thickness of the block from the front or weather face of the block, although this location is not absolutely essential. The block is of such size that the edges of the side strips 13 are flush with the upper and lower faces of the block, while the hooks 12 project beyond the ends of the block.

In building a wall from the above described reinforced concrete blocks, the blocks to make up any given course are placed end to end in the usual manner which brings the hooks at the end of one block against those at the end of an adjacent block, as clearly shown in Fig. 6 of the drawings. U-shaped anchoring strips 32 of sheet metal are then applied in the manner shown in Fig. 6, each locking one of the hooks of one block to the abutting hook of the next block and the two together holding each other against displacement. These locking members 32 are preferably embedded in a liquid metal cement which will later set to form a waterproof joint and any suitable form of cement or mortar 33 may be employed to close the remainder of the joint between the blocks. As a means for holding the blocks of one course against lateral movement with respect to the blocks of adjacent courses and also as a means for providing waterproof horizontal joints between courses, I employ locking strips 34 of sheet metal which seat in the alined channels 14 along the top and bottom edges of the blocks formed between the strips 13 and which are set in the same metal cement. A thin layer 35 of cement or mortar is interposed between the courses of blocks.

From the foregoing description, it will be apparent that with any wall constructed with such reinforced concrete blocks it will be impossible for water or moisture to pass through the block as an absolutely water tight metallic partition wall coextensive with the concrete wall is formed by the reinforcing structures and water tight joints between them. At the same time, the various anchoring devices or reinforcing elements 19, 27, 28 and 30 being embedded in the concrete, positively bind all the parts together so that the block has greater tensile strength than any concrete block of corre-

sponding dimensions not having the metallic reinforcement.

In Figs. 8 to 10 inclusive, I have illustrated a metallic reinforcement to be employed in the construction of monolithic concrete walls. This reinforcement is identical with that previously described, except for certain additional elements. Anchoring plates 36 are riveted or otherwise secured against opposite sides of the body 10 at suitable points, such as at diametrically opposite portions of the central part of the body, as shown in Fig. 8, and have threaded sockets to receive rod or pipe sections 37 which extend at right angles to the body 10 and which, at their ends, are connected by unions 38 with vertical rod or pipe sections 39. These pipe sections, secured to the body as described, greatly increase the strength of the wall, and they may be longer or shorter according to the thickness of the wall. In addition to these supplemental anchoring members I provide centering fingers 40 in the form of strips of sheet metal secured to opposite sides of the lower edge of the body 10 and projecting beyond such edge having pointed terminals 41. The free ends of these centering fingers are adapted to straddle the upper edge of a subjacent body section to insure bringing the channels 14 of such sections into alignment with each other to properly seat the anchoring strips 34. Of course, in building the wall, the reinforcing elements are assembled and connected with each other as the work of building the wall progresses, the various anchoring members being applied in each instance just prior to the application of that layer of concrete which will embed them.

Although I have illustrated and described my invention in all its details of construction, it will of course be understood that I do not limit myself to such details but reserve the right to make changes, within the scope of the appended claims, without in the slightest degree departing from the spirit of my invention.

Having thus described the invention, what is claimed as new is:

1. In concrete construction, a cementitious body, a plate of sheet metal embedded therein between and parallel with the side faces thereof and substantially co-extensive therewith, a plurality of anchoring members extending from each face of the plate adjacent the side and end edges thereof, and other anchoring members extending laterally from each face of the plate intermediate the edges thereof.

2. In concrete construction, a cementitious body, a plate of sheet metal located within the cementitious body between its front and rear faces, the upper and lower edges and end edges of the plate being substantially in the plane of the upper and lower and end

faces of the body respectively, and a plurality of laterally extending anchoring members carried by the plate and embedded in the cementitious body, some of said anchoring members having laterally directed anchoring heads at their free ends. 70

3. In concrete construction, a cementitious body, a plate of sheet metal located within the body between the front and rear faces thereof with its upper and lower edges and end edges substantially in the plane of the upper and lower and end faces of the body respectively, and a plurality of anchoring members carried by the plate and embedded in the cementitious body, some of said anchoring members forming bows projecting laterally from the plate. 75 80

4. In concrete construction, a cementitious body, a plate of sheet metal located within the body between the front and rear faces thereof with its upper and lower edges and end edges substantially in the plane of the upper and lower and end faces of the body respectively, and a plurality of anchoring members carried by the plate and embedded 85 90 in the cementitious body, some of said anchoring members forming bows projecting laterally from the plate and some of the anchoring members being sheet metal strips having laterally bent terminals. 95

5. In concrete construction, a cementitious body, a plate of sheet metal embedded in the cementitious body, strips of sheet metal secured to opposite faces of end portions of the plate and provided with relatively wide 100 longitudinal slots, other strips of sheet metal secured upon the first-named strips and provided with relatively narrow longitudinal slots overlying the slots in the first-named strips, and anchoring members having 105 shanks passing through the relatively narrow slots, and heads seating in the wider slots in the first-named plates.

6. In concrete construction, a cementitious body, a plate of sheet metal embedded in 110 the cementitious body, sheet metal strips secured longitudinally upon the face of the plate, pockets on said strips at intervals along the same, and anchoring members having hooks at their inner ends seating in 115 the pockets and having lateral heads at their outer ends.

7. In concrete construction, a cementitious body, a plate of sheet metal embedded in the cementitious body, sheet metal strips secured to the face of the sheet metal plate and extending longitudinally thereof adjacent its upper and lower edges and at an intermediate point of its height, pockets on the several longitudinal strips, anchoring members having lateral heads at their outer ends and hooks at their inner ends fitted in the pockets on the upper and lower strips, and anchoring loops having their ends fitted in pockets on the intermediate strips. 125 130

8. In concrete construction, a cementitious body, a plate of sheet metal embedded in the cementitious body, sheet metal strips secured longitudinally upon the face of the plate, 5 pockets on said strips at intervals along the same, anchoring members having hooks at their inner ends seating in the pockets and having lateral heads at their outer ends, sockets secured on the face of the plate be- 10 tween the longitudinal strips, bars secured in said sockets, and other bars secured to the outer ends of the first-mentioned bars and extending at an angle thereto.

9. In concrete construction, a cementitious body, a plate of sheet metal embedded there- 15

in, sheet metal strips secured upon the face of the plate and extending longitudinally thereof adjacent its upper and lower edges and at an intermediate point of its height, pockets on the several strips, anchoring 20 members having lateral heads at their outer ends and hooks at their inner ends fitted in the pockets of the upper and lower strips, and anchoring loops having their ends fitted in the pockets on the intermediate strip, the 25 ends of one loop being disposed between the ends of adjacent loops whereby the bowed portions of the loops overlap.

In testimony whereof I affix my signature.
JEROME W. WELCH. [L. s.]
